UNITED STATES PATENT OFFICE.

HERMAN L. GREVE, OF BROOKLYN, NEW YORK.

ADJUSTABLE CUFF BUTTON.

Application filed February 20, 1925. Serial No. 10,490.

My invention relates to cuff buttons for use with shirts having cuffs made of soft flexible material and in which the outer exposed portion of the cuff is folded back over the sleeve portion in adjustable relation thereto.

The object of my invention is to provide cuff buttons to be sold in pairs as heretofore, the button construction for each cuff comprising means whereby the cuff of the shirt may be adjusted to increase or decrease its length, and to present a number of different wearing edges.

Referring to the drawings which form a part of this specification,

Fig. 1 is an illustrational view of a portion of a shirt sleeve having a soft cuff in which is shown a cuff button construction embodying my invention, the long shank portions extending toward the front edge portion of the cuff.

Fig. 2 is a similar view showing the said shanks extending in the opposite direction in the cuff.

Fig. 3 is a vertical sectional view of a cuff showing the button construction on an enlarged scale, whereby its construction and use may be more definitely understood.

Fig. 4 is a vertical elevational front view showing the movable link portion mounted on the shank of display button portion.

Fig. 5 is a view of the back of a link portion.

Fig. 6 is a view of the back of the display button and the corrugated shank, the flat spring portion being broken from the bottom end of the shank.

A, indicates a portion of a shirt sleeve with an inner cuff portion A' connected directly thereto at the seam A'. Formed integral with the cuff portion A' is an outer or exposed cuff portion, B, which is folded back over the inner portion as illustrated and each portion is provided with button holes, those formed in the outer portion being indicated by C—C and those formed in the inner portion by C'—C' respectively.

D, indicates the display buttons and F indicates the link portions which may be formed like a button as illustrated or may have any other suitable form so long as they serve the purpose of linking the two side portions of the cuff together, and are hereinafter referred to as the links or link members.

Each button D is provided with a short

shank portion D' and an extension thereof indicated by F, comprising a thin flat strip of metal which is bent back upon itself at F² to form a spring action between the portions F and F'. Either the limb F or F' or both, may be formed to provide the corrugations G—G etc., or one only having said corrugations and the other limb left plain as illustrated by the limb F. I prefer however to corrugate the limb F as illustrated. The link E is provided with a shank E' provided with an opening E² of sufficient size to permit the limbs F and F' to project therethrough in sliding engagement and having an inwardly extending portion E³ adapted to enter a depression of the corrugation to hold the link E in its adjusted position on the limb by reason of the spring action exerted by the spring formed at F². One of the link members E is provided with a recess H and the coacting link is provided with a projection H' by means of which the links are held together in a manner well known to this art.

Each button is attached to a cuff by passing the limbs F and F' through a button hole C so that the limbs rest between the cuff portions B and A'. The shank of a link E is then passed through the adjacent hole C' of the portion A', and the shank portions F and F' are slipped through the opening E² and as it moves through said opening, the display button, moving with the shank, carries the outer cuff portion B downward, thus increasing the length of the cuff on one side, after which the opposite button is attached to the cuff in the same manner, and the two adjacent links E—E connected together in the usual manner, and thereafter the cuff may be increased or decreased in its length within the limits of the movement of the shank through the link E. By moving the display buttons D, downward relative to the links E, the cuff is lengthened and the lower edge becomes a part of the inner cuff portion A', thus presenting a new edge portion for wear.

Instead of bending the limb F to form the transverse grooves or corrugated surface, the grooves could be formed on one side only of this limb, so long as anchorages are provided to hold the link E in adjusted relation to shank. Many detail changes may be made in the construction without departing from the invention disclosed and I do not wish to be limited to the exact means shown

for holding the link portion to the shank portion of the button in adjustable relation.

Having thus described my invention I claim as new:

5. 1. Means for holding a shirt cuff comprising a pair of buttons each having a shank portion adapted to lie in the fold of a cuff and a link portion adapted to engage said shank portion and be held thereon in adjustable relation.
10. 2. Means for holding a shirt cuff comprising a pair of buttons each having a shank portion adapted to lie in the fold of a cuff and a link portion adapted to engage said shank portion, and means for holding said portions together in adjustable relation.
15. 3. Means for holding a shirt cuff comprising a pair of buttons each having a shank portion adapted to lie in the fold of a cuff and having a corrugated surface, and a link portion having means for engaging the shank portion and held in adjusted relation thereon by a corrugated portion thereof.
20. 4. Means for holding a shirt cuff comprising

ing a pair of buttons each having a shank portion adapted to lie in the fold of a cuff and a link portion adapted to engage said shank portion and be held thereto in adjustable relation.

5. Means for holding a shirt cuff comprising a pair of buttons, one having a shank embodying a spring located in the fold of the cuff and one having a link adapted to releasably grip said shank within the fold and retain the sides of the cuff relatively close together.

6. Means for holding a shirt cuff comprising a pair of buttons, one having a shank embodying a spring located in the fold of the cuff and one having a slotted link adapted to frictionally engage the surface of said shank within the fold and retain the sides of the cuff relatively close together.

In testimony whereof I, HERMAN L. GREVE have signed my name to this specification this 10th day of February 1925.

HERMAN L. GREVE.
